UNITED STATES PATENT OFFICE

103,811

DESIGN FOR A VEHICLE

Paul O. Dittmar, Evanston, Ill.

Application December 14, 1936, Serial No. 66,513

Term of patent 3½ years

To all whom it may concern:

Be it known that I, Paul O. Dittmar, a citizen of the United States, residing at Evanston, Cook County, Illinois, have invented a new, original, and ornamental Design for a Vehicle, of which the following is a specification, reference being had to the accompanying drawing, forming a part thereof.

Fig. 1 is a side elevation of the vehicle, showing my design.

Fig. 2 is a front elevation of the vehicle.

Fig. 3 is a rear elevation of the vehicle.

The dominant feature of my design resides in the portions illustrated in solid lines.

I claim:

The ornamental design for a vehicle, as shown and described.

PAUL O. DITTMAR.
